UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

WASTE-VALVE MECHANISM.

Application filed April 23, 1923. Serial No. 633,952.

To all whom it may concern:

Be it known that I, ORVIS W. VALLIER, a citizen of the United States, residing at Watertown, in the county of Jefferson and 5 State of New York, have invented certain new and useful Improvements in Waste-Valve Mechanism, of which the following is a specification.

This invention relates to a waste valve mechanism, designed for use in connection with lavatories, baths, and the like, and has for its object to provide a novel and simple mechanism, by which the ordinary "pop-up" stoppers may be reciprocated, for opening and closing the waste outlets. And a further object is to generally improve, simplify and cheapen the construction and operation of waste valve mechanisms of the class.

20 I attain these objects by the means set forth in the detailed description which follows, and as illustrated by the accompanying drawing, in which—

Figure 1 is a central vertical section 25 through a basin and related parts, to which my improvement is applied. Fig. 2 is a detached view of the operating plunger and related operating parts. Fig. 3 is a detached view of one form of waste stopper. 30 Fig. 4 is an enlarged fragmentary view of the plunger and disc. Fig. 5 is an edge view of the same. And Fig. 6 is an edge view of the disc.

In the drawing, 2 represents an ordinary 35 lavatory, which is supported at 3, and 2' is the waste opening in the bottom of the bowl 2. 4 represents the usual waste bushing that extends below and guides the stopper 5, the upper end of the latter being 40 formed with a bevel disc or head, which conforms to an annular seat 4' of the bushing. To the lower end of the bushing 4 is secured a T 6, into which the lower end of the stem 5' of the stopper extends, the said 45 end being provided with a horizontal slot 5'. The stopper 5 is raised and lowered by means of a rod 7, whose inner end plays in the slot 5', and is bent, as at 7', for producing a crank-like movement when the rod 50 is rotated, for reciprocating the stopper (see the full and dotted lines in Fig. 1). The rod 7 extends laterally through the arm 6' of the T, and is operatively supported 55 by a bushing 8, whose inner end screws into the arm 6', and also by a gland-nut 9, which

screws into the outer end of the bushing. Intermediate its ends, the rod 7 is formed with a rigid enlargement or sleeve 7', which is confined between a shoulder 8' of the bushing, and a washer 10, which prevents 60 longitudinal movement of the rod. Between the nut 9 and the washer 10 is disposed a packing 9', for preventing leakage around the rod. The rod 7 extends beyond the nut 9 a considerable distance, and adjustably 65 supports a disc 12, which is rigidly secured to the rod by a set-screw 12'. The disc proper is formed like a spool, having a short barrel 12', and similar circular end portions 12"—12" of larger diameter, which comprise 70 the chines and form a continuous peripheral groove, and the periphery of the barrel is formed with a notch or socket 12". The disc 12 and the rod 7 are rotated on a horizontal axis, as one part, by a manually operable plunger 13, which is movable vertically in an opening 2' of the basin 2, as well as in a relatively long tubular guide 14, which is encased in and is supported by a 75 sleeve 15. The top end of the plunger is 80 preferably fitted with a hand-knob 13', which projects above, and is normally supported, by a head 14' of the tube. The sleeve 15 is held in place by a nut 15', which screws on to the lower threaded end of the 85 tube 14. The lower threaded end of the plunger 13 adjustably supports an inverted L-shaped member 16, the latter having a plane body 16', which has an oval opening 16", that loosely receives the barrel of the 90 disc 12, while the chines 12"—12" overlap the opposite faces of the body 16', and operatively hold the parts together. At one side of the opening 16" is formed an inwardly facing tooth 16", which normally engages the socket 12" of the barrel 12', so that when the plunger is raised or lowered, the tooth 16" rotates the disc 12 and shaft 7 (see full and dotted lines in Figs. 1 and 4), and correspondingly raises and lowers 95 the stopper 5, for opening and closing the waste outlet 2'. It will be understood, that the principle upon which the member 16 and the disc 12 operate, is practically the same as that of the ordinary rack-and-pinion gearing, wherein the pinion, in the present case, has a fixed axis, while the rack is reciprocated for rotating the pinion.

It is desirable, in a mechanism of the class herein shown and described, when the 100

stopper 5 is raised for draining the bowl 2, that the said stopper, as well as the plunger 13, and the various connecting parts, shall remain in the operated positions until the 5 time arrives for closing the outlet 2'. To this end, the plunger 13 preferably snugly fits the relatively long tube 14 to an extent that requires some force to overcome the frictional engagement of said parts. Furthermore, the enlargement 7^a of the rod 7, 10 when properly disposed in the bushing 8, may be subjected to enough tension by the tightening of the nut 9, to prevent the accidental rotation of the rod, and the consequent shifting or lowering of the stopper 15 and plunger.

The provision of the T 6, and the peculiar construction of the bushing 8 and the rod 7, with which are associated the novel actuating means comprising the disc 12 and its 20 operating member 16, constitute a reliable and smooth-working valve mechanism, which performs its work positively, readily and quietly, and requires little or no attention or care after it is once properly installed. The adjustment provided between the plunger 13 and the member 16, as well as the means for adjusting the disc 12 relatively to the rod 7, renders my mechanism 25 readily adaptable to the varying measurements with which plumbers frequently have to contend with, without requiring any alterations, or any new parts. Furthermore, the entire absence of the usual loose and 30 noisy parts, renders the present mechanism less liable to become impaired or disordered, than any of the older waste operating mechanisms known to me.

Having thus described my invention, what 40 I claim, is—

1. A waste valve mechanism, including a valve, a crank-rod, operatively connected with said valve, a disc carried by said crank-rod having a socket; and a reciprocatable member having an opening to operatively receive said disc and having an inwardly facing tooth engaging said socket for rocking said crank-rod.

2. A waste valve mechanism, including a reciprocatable valve, a rock-shaft having one end operatively engaging said valve, a disc rigid on the opposite end of said shaft having a peripheral socket, a member reciprocatable in the plane of said disc, and having a tooth engaging said socket for rocking the said shaft.

3. A waste valve mechanism, including a reciprocatable valve, a rock-shaft having one end operatively engaging said valve, a disc rigid on the opposite end of said shaft 60 having a peripheral socket, a member movable in the plane of said disc having an opening for loosely receiving the disc, said opening being elongated whereby said member may be moved relatively to the disc, and 65 said member having a tooth projecting into the opening and engaging said socket for reciprocating said valve.

4. In a waste valve mechanism, a basin having an outlet opening in its bottom, a valve for controlling said outlet, said valve having a stem extending below the basin, a T inclosing the lower end of the valve stem, a bushing supported by said T, a rotatable rod for raising and lowering said valve, said rod journaled in said bushing and having an enlargement within the bushing, means for exerting tension against said enlargement for preventing the endwise movement of the rod, a disc adjustably mounted on said rod beyond said bushing, a reciprocatable member having an opening to receive said disc and having a tooth adapted to rotate said disc, and means for reciprocating said member.

5. In a waste valve mechanism for lathes and the like, the combination with a waste conduit, and a valve for closing said conduit having a depending stem, of a crank-rod for raising and lowering said 90 valve, one end of said rod engaging said stem, a T supported by said conduit, a bushing supported by said T and forming a bearing for said rod, tension means carried by said rod adapted for preventing accidental rotation of said rod, a disc mounted on said rod beyond said nut having a socket, a reciprocatable member having a tooth engaging said socket adapted to rock said disc and said rod, and a plunger 100 adjustably connected to said member.

6. In a waste valve mechanism, the combination with a waste conduit, a valve for closing said conduit, and a crank-rod for operating said valve, of a disc adjustably and rigidly mounted on said rod having a 105 socket, and a reciprocatable member having a tooth engaging said socket for rotating said disc and crank-rod for raising and lowering said valve.

In testimony whereof I affix my signature.
ORVIS W. VALLIER.
